UNITED STATES PATENT OFFICE

168,002

PICKUP ARM FOR PHONOGRAPH

Herbert Vaughan Slade, Swindon, England, assignor to The Garrard Engineering and Manufacturing Company Limited

Application January 3, 1952, Serial No. 17,916
In Great Britain August 30, 1951

Term of patent 7 years

(Cl. D26—14)

To all whom it may concern:

Be it known that I, Herbert Vaughan Slade, subject of the King of Great Britain and Ireland, residing at Swindon, Wiltshire, England, have invented a new, original, and ornamental Design for a Pickup Arm for Phonograph, of which the following is a specification, reference being had to the accompanying drawing, forming part thereof.

Fig. 1 is a side elevational view of a pickup arm for a phonograph showing my new design.

Figure 2 is a top plan view thereof.

Figure 3 is a bottom plan view and

Figure 4 is a top perspective view of the same.

I claim:

The ornamental design for a pickup arm for phonograph, as shown.

HERBERT VAUGHAN SLADE.
